UNITED STATES PATENT OFFICE.

LOYAL A. COUCH, OF NEW YORK, N. Y.

FUEL-HEATER FOR INTERNAL-COMBUSTION ENGINES.

1,389,029.

Specification of Letters Patent. Patented Aug. 30, 1921.

Application filed January 14, 1920. Serial No. 351,396.

To all whom it may concern:

Be it known that I, LOYAL A. COUCH, a citizen of the United States, and a resident of New York, in the county of New York and State of New York, have invented certain new and useful Improvements in Fuel-Heaters for Internal-Combustion Engines, of which the following is a specification.

My invention relates to improvements in internal combustion engines, it being more particularly an improvement in fuel heaters for such engines, and it consists in the constructions, combinations and arrangements herein described and claimed.

The foremost object of my invention is to provide a simple, electrically operated fuel heater, which consists principally of a fine resistance disposed across the current of carbureted air, for the purpose of heating this air before it enters the intake manifold.

A further object of the invention is to provide an electrical resistance for the purpose described, the wires of which are so fine that the flow of air will not be impeded.

Other objects and advantages will appear in the following specification, reference being had to the accompanying drawing, in which:—

Figure 1 is a front elevation, partly in section, illustrating the application of the improved heater between the intake manifold and carbureter connection,

Fig. 2 is a detail plan view of the heater mounting,

Fig. 3 is a longitudinal section on the line 2—2 of Fig. 2,

Fig. 4 is a plan view of the mounting with the insulating resistance-carrying collar in place, a part being shown in section to illustrate a binding screw,

Fig. 5 is a detail plan view of the insulating collar,

Fig. 6 is a partial elevation and section taken substantially on the line 6—6 of Fig. 5, and

Fig. 7 is a diagram of the wiring connections.

In carrying out my invention I provide a mounting 1 which is shaped substantially like the flanges 2 and 3 of the manifold and carbureter connections 4 and 5 respectively, and is preferably made of brass. This mounting has a central opening 6, merging with a semi-circular annular recess 7 and an annular recess 8 of greater dimension, for the purpose of providing the shoulder 9.

At one side there is a recess 10 with a counterbore 11. The insulating collar 12, which carries the fine resistance wire 13, is mounted in the opening 6 as clearly shown 60 in Fig. 1.

The semi-circular annular recess 7 is for the purpose of making room for those portions of the resistance wire 13 threaded on the outside of the collar, the space left 65 around the exposed parts of the wire, preventing metallic contact.

When the parts are assembled as in Fig. 1, the flange 14 of the collar 12 is clamped between the flanges 2, 3 so that the heating 70 element is firmly held in place. One end of the resistance wire 13 is grounded at 15, the other end running to the binding screw 16 which occupies the counterbore 11 but is insulated by suitable washers and sleeve 17, 18. 75

In operation the starter switch S_w is closed so that current flows from the battery B over wire 19, through switch S_w , starter S and returning to the negative pole of the battery via wire 20 and the ground connections. The current divides and in part energizes the resistance web 13, thereby generating heat at the same time that the engine is started.

As is obvious from the foregoing, the improved heater is adapted more particularly for use in cold weather when it is difficult to start the engine by reason of the cold fuel. Practice has demonstrated that the application of heat to the fuel before it enters the 90 intake manifold, makes the starting of the engine easy.

As pointed out above, the wires of the resistance 13 are so fine that the flow of gas is not impeded. The energization of the 95 heater occurs simultaneously with the starting of the car. There are only two main pieces in the improved heater, namely, the brass mounting 1 and the insulating collar 12 with its resistance web.

While the construction and arrangement of the improved heater as herein described and claimed, is that of a generally preferred form, obviously modifications and changes can be made without departing 105 from the spirit of the invention or the scope of the claims.

I claim:—

1. A fuel heater, comprising a mounting, and an insulating collar fitting in an opening in the mounting, with carried resistance means, said opening being arranged to 110

avoid contact with exposed portions of said means.

2. A fuel heater, comprising a metallic manifold flange-shaped mounting, with a central opening having a semi-circular annular recess and a larger annular recess forming an intermediate shoulder; an insulating collar occupying said opening, with a flange resting in the larger recess against

said shoulder where it is fastened; a fine resistance wire threaded across the collar from side to side, the exposed portions occupying the semi-circular recess to keep from touching, one end of the wire being grounded; and a binding screw insulatively mounted at one side of said mounting, receiving the other end of said wire. 10 15
